UNITED STATES PATENT OFFICE.

JOHN CLIFFORD MERWIN, OF MILWAUKEE, WISCONSIN, ASSIGNOR TO CHAIN BELT COMPANY, OF MILWAUKEE, WISCONSIN, A CORPORATION OF WISCONSIN.

SAFETY GUARD.

Application filed March 20, 1922. Serial No. 545,130.

To all whom it may concern:

Be it known that I, JOHN CLIFFORD MERWIN, a citizen of the United States, residing at Milwaukee, in the county of Milwaukee and State of Wisconsin, have invented certain new and useful Improvements in Safety Guards, of which the following is a specification.

In many concrete mixers particularly those of large size and such as are constructed for use in paving operations, it is customary to dump the solid ingredients that enter into a single charge of the mixer into a loading skip, that is connected with the framework surrounding the mixer and is arranged to be lifted and tilted so that its charge will slide or spill into the mixing drum. After being thus emptied it is returned to the ground to receive the ingredients of another charge which are commonly dumped into it from trucks, loading buckets, or barrows. When the loading skip is in its elevated and charging position it is high above the ground, and it is common practice to return it to its lower position to receive the next charge rapidly. It also sometimes happens that a skip will fall from its elevated position through breakage of parts or other accidental reason. The falling of a charging skip, and even its return to its lowermost position under normal working conditions, are attended with more or less danger to workmen who may carelessly pass under the skip when raised, for it is a large and ponderous object, and since it moves in descending with much rapidity a blow therefrom is liable to be attended with serious results.

My invention has for its object to provide such a loading skip or other analogous mechanical device, with a guard that automatically comes into position to prevent a person passing below the skip or other device when raised.

In the accompanying drawings I illustrate the invention applied to a concrete mixing machine.

Figure 1 is a side elevation of a machine embodying my invention, showing the loading skip in its lowermost position by full

lines and in its elevated position by dotted lines.

Fig. 2 is a side view of a different embodiment of the invention.

Fig. 3 is a plan view of the guard detached from the mixing machine.

In the drawings, 2 indicates a mixing drum, and 3 the framework surrounding it, of a portable concrete mixing machine such as is used in paving operations.

4 indicates the loading skip, adapted when in its lowermost position, shown in full lines, to rest upon the ground so that it may be loaded by hand from wheel barrows, or from a truck backed up to the end of the skip, which end is open as is common in apparatus of this kind. After a charge of the solid ingredients that enter into a single batch of concrete have been placed in the skip, it is elevated, as by the cables 5, into the position represented by dotted lines, Fig. 1, and the charge then slides from the skip into the mixing drum 2, after which the skip is returned to its lowermost position to be again loaded.

The mechanism controlling the movements of the skip is not illustrated in detail, since it is well known in the art and forms no part of the present invention. The skip-controlling mechanism so far as shown comprises pulleys 18 over which pass the cables 5, the small pulleys or drums 19 upon which the cables are wound, and the larger drum 20 constituting a part of the cable winding and controlling mechanism. In the form of invention represented in Fig. 1 the skip is provided with pivot bars 6, secured fast to its spout end and pivotally united with the framework 3, at 7. The parts thus far described are all of well known construction.

A guard to serve as a warning not to enter the space below the charging skip when it is in its elevated position, is supported by the framework of the mixing machine and it is adapted to be supported at a suitable height above the surface of the ground below the skip. This guard consists of a pair of longitudinal bars 8, 8 and a cross bar 9 connecting them at their outer ends.

The inner ends of the bars 8 are pivoted, at 10, to some convenient part of the framework of the machine, as for instance, to the longitudinal sills 11. The distance between 5 the bars 8, 8 is preferably such that they lie comparatively close to the sides of the skip when the latter is in its lower position. The bars may be straight and parallel or they may be fashioned to follow the outlines of 10 the sides of the skip, as may be desired, this being a matter of construction not pertaining to the invention.

They are preferably of such length that 15 the cross bar 9 lies under the bottom of the skip near its front edge when the skip is lowered, as shown in Fig. 1.

The guard has combined with it means 20 that cause it to maintain the desired extended position above the surface of the ground and beneath the skip when the latter is raised. In practice it extends out from its pivotal supports 10 substantially horizontally and is about three feet from the surface of the ground.

25 Various means may be employed for controlling the movements of the guard. For instance, in the form of invention shown in Fig. 2, springs 12, one near each pivot 10, act on the guard and lift it to guard- 30 ing position when free to do so. The bars 8 are extended beyond the pivots 10, to form short arms 13, and these, in the form of invention shown in Fig. 2, are adapted to engage with stops 14 carried by the sills 11 35 to arrest the guard when the springs have lifted it to the desired position to act as a barrier and warning to persons moving in the vicinity of the mixer. As the skip descends it falls between the side bars 8 and 40 its bottom comes into contact with the cross bar 9 and carries the guard downward along with the descending skip to the position indicated in Figs. 1 and 3.

45 In Fig. 2 the skip does not have the pivot bars 6 but carries perforated lugs 24 by which it may be pivotally connected with the framework of the mixer, an arrangement that is to be preferred in some types of mixing machines to that illustrated in 50 Fig. 1.

55 In the form of invention illustrated in Fig. 1 the short angularly arranged arms 13 of the side bars 8 are connected by links 15 with arms or cranks 16 extending radially from the pivots 7. The arms 16 60 may be secured fast either to the pivot bars 6 or to the pivot pins 7, the important feature being that the crank arms 16 move synchronously with the movements of the charging spout and preferably about the same axis. The relative lengths of the crank arms 16 and the arms 13 are such that while the charging skip moves from the lowermost position shown in full lines to its 65 upper discharging position, the guard moves

a much less distance, from the full line position to that represented in dotted lines.

70 While the two sets of operating means shown for causing the movements of the guard are both practical, other means for effecting the movements described may be employed, since the invention is not limited to the specific means that may be used for effecting the movements described.

75 It will be seen that the guard in nowise interferes with the operation of the skip. When the latter is in its lower position to be loaded the guard lies close alongside the skip with its cross bar 9 under the floor of the skip and does not interfere with the 80 movements of the wheel barrows or other instruments employed in loading.

85 The guard described may be cheaply manufactured and easily applied to machines that are already in use as well as to new machines as part of their original equipment.

What I claim is:

1. The combination with a pivoted skip and means for raising and lowering it, of a 90 guard supported adjacent to the skip and means for moving the latter to a protective position above the surface of the ground and below the skip when the latter is raised.

95 2. The combination with a loading skip and means for elevating it for the purposes of discharge and lowering it to the ground where it may be loaded, of a guard for enclosing the space below the skip when it is raised, and means operating when the skip 100 is elevated to move the guard to position between the surface of the ground and the skip.

105 3. The combination with a loading skip and means for controlling its movements while being elevated and lowered, of a guard arranged when the skip is lowered to be engaged thereby and moved toward the surface of the earth, and means for lifting the guard when the skip is raised to position 110 to discharge.

115 4. The combination with a loading skip, a support by which it is carried and means for controlling its movements while it is being elevated and lowered, of a guard supported by the said support and arranged to surround the space below the skip when the latter is elevated and so prevent persons passing under the skip, and means for raising the guard into operative position when 120 the skip is raised and for moving it into such position that it shall not interfere with the loading of the skip when the latter is lowered.

125 5. The combination with a loading skip, means for controlling its movements while being elevated and lowered, and a supporting frame by which the skip is carried, of a guard supported by the said frame and comprising a pair of side bars and a cross bar, 130

the latter being adapted to lie between the bottom of the skip and the ground when the skip is lowered, and means for raising the guard when the skip is raised so that it encloses the space below the skip.

6. The combination with a loading skip and means for controlling its movements while being elevated and lowered, of a pivoted guard enclosing a space below the skip when elevated, and means connected with the skip for operating the guard arranged to lift the latter to a position above the surface of the ground when the skip is raised, and to lower the guard when the skip is lowered.
- 10

7. The combination with a pivoted loading skip and means for controlling its movements, of a pivoted guard having side bars and an outer cross bar, the latter being arranged to lie between the bottom of the skip and the ground when the skip is lowered, a crank arm arranged to be moved when the skip is moved on its pivot, and connections between the crank arm and the guard arranged to elevate the guard to a position above the ground and directly below the skip when the latter is raised and to lower the guard when the skip is lowered.

JOHN CLIFFORD MERWIN.
